CLAIM

The ornamental design for a pitcher with a lid, as shown and described.

DESCRIPTION

FIG. 1 is a top perspective view of a pitcher with a lid with the lid removed for ease of illustration showing my new design;

FIG. 2 is a bottom perspective view thereof;

FIG. 3 is a left side view thereof;

FIG. 4 is a top plan view thereof;

FIG. 5 is a right side view of the pitcher with lid where the lid is on the pitcher;

FIG. 6 is a top perspective view of the pitcher with lid with the pitcher removed for ease of illustration; and,

FIG. 7 is a bottom perspective view thereof.
